LIQUID ATTEMPERATING DEVICE

Fritz G. Cornell, Jr., Mountain Lakes, N. J., assignor to Jensen Creamery Machinery Company, Inc., Bloomfield, N. J., a corporation of New York

Application January 2, 1936, Serial No. 57,319

7 Claims. (Cl. 257—104)

This invention relates to liquid attemperating devices and more particularly to apparatus for attemperating liquid dairy products.

An object of this invention is an apparatus of this type in which very uniform circulation and rapid attemperating of the dairy product is effected. A further object of the invention is an apparatus of this type in which the construction is such as to permit easy and complete access to the interior surface wall of the apparatus for cleaning and in which the top of the apparatus is completely free of driving mechanism.

In one embodiment of the invention, a vat contains a vertical helical coil which is rotatably supported by means extending upwardly from the bottom of the vat and driving mechanism for the coil is located below the bottom of the vat. A vertical baffle plate is supported within the coil. The liquid dairy product to be attemperated is charged into the vat and the coil is rotated while attemperating fluid is caused to circulate therethrough. The baffle plate prevents swirling of the liquid within the coil, thereby preventing the formation of a vortex in the liquid and uniform circulation is produced in the body of the liquid inside the coil with accompanying circulation of the liquid between the turns of the coil. The circulation thus produced causes rapid and quick contact of the liquid product with the attemperating surface, thereby resulting in very rapid attemperating of the product. The attemperating coil may preferably be made of general elliptical formation, thus providing clearance between the coil and the vat wall to give access to the wall for cleaning purposes without reducing the total contact surface of the coil. Also, the elliptical configuration of the coil assists in effecting circulation of the product in the vat.

In another embodiment of the invention, the vat is equipped with a jacket through which attemperating medium is circulated and a helical agitator is supported from its upper end by the means extending upwardly from the bottom of the vat. The agitator is rotated in such direction as to remove air, gases and volatile odors from the dairy product and at the same time prevent air being worked into the product. The agitator effects such circulation of the dairy product as to cause rapid and quick contact thereof with the attemperating surface, thereby resulting in rapid attemperating of the product. The agitator is preferably removable from its supporting means to provide for access to the wall of the vat for cleaning purposes.

Other objects, novel features and advantages

of this invention will become apparent from the following specification and accompanying drawing, wherein:

Fig. 1 is a plan view of one embodiment of the invention with the cover removed;

Fig. 2 is a vertical section partly broken away;

Fig. 3 is a vertical section through a portion of the supporting means for the coil.

A frame or support 10 contains a vat 11 having its bottom sloping toward a discharge outlet 12 and being provided with a removable cover 13. A hollow post or standpipe 14 has its base 15 resting on the bottom of the frame 10 and extends through the bottom of the vat 11 above the normal liquid level in the vat. A hollow shaft 16 has an enlarged head 17 which is journaled in a stuffing box bearing 18 at the top of the standpipe 14. The lower end of the shaft 16 is likewise provided with a head 19 which is journaled in a stuffing box bearing 20 provided in a housing 21 suspended from the bottom of the frame 10. Within the shaft 16 is provided a tube 22, the upper end of which communicates with a duct 23 provided in the head 17 while the lower end communicates with a duct 24 provided in the 25 housing 21.

A coil 25 surrounds the post 14 and has its inlet 26 communicating with the duct 23 and its outlet 27 communicating with the annular space between the tube 22 and shaft 16, which space in 30 turn communicates with the duct 28 in the housing 21. The coil is in effect composed of two lengths of tubing arranged side by side in the form of helices and connected at their bottom. A worm wheel 29 is fixed to the shaft 16 below 35 the bottom of the frame 10 and meshes with a worm gear 30 driven by the motor 31. Baffle plates 32 are carried by the post 14 and terminate above the bottom of the vat and below the top of the coil. Preferably, the coil is of substantially 40 elliptical configuration.

In using this embodiment, the dairy product to be attemperated is charged into the vat 11 and the coil 25 is rotated by the motor 31. Attemperating fluid is supplied to the duct 24 and 45 passes upwardly through the tube 22 by way of the duct 23 into the inlet 26 of the coil 25, downwardly through one section of the coil and upwardly through the other section, out through the duct 27 into the space between the tube 22 50 and shaft 16, downwardly through said space to the duct 28 from which it is discharged. The baffle plates 32 prevent the formation of a vortex in the liquid. Likewise, the coil itself by reason of its elliptical configuration effects agitation of 55

the product and permits circulation of the product between the turns of the coil.

The arrangement of the driving mechanism below the bottom of the frame permits easy access to the interior of the vat and facilitates charging the vat with liquid product as well as obviates the inconvenience of having the driving mechanism above the vat. With the arrangement above described, access to the wall of the vat for cleaning purposes is provided by the elliptical contour of the coil which can be rotated as desired to give access progressively to the entire surface. The same amount of contact surface may be provided as has been provided in circular coils supported from above the vat inasmuch as less clearance is required at the ends of the ellipse.

It is of course understood that various modifications may be made in the device above described, without in any way departing from the spirit of the invention as defined in the appended claims.

I claim:

1. An attemperating apparatus of the character described comprising a vat, rotatable means supported by said vat, a vertical helical coil of elliptical cross-section open at its lower end attached at its upper end only to said means and being centered on the rotational axis thereof, a stationary baffle plate supported within said coil, and means to circulate fluid through said coil.
2. An attemperating apparatus comprising a vat, a stationary vertical post in said vat extending upwardly from the bottom thereof above the normal liquid level therein, a vertical coil of elliptical cross-section open at its bottom rotatably supported at its upper end only by said post and extending downwardly below the normal liquid level, said coil being centered on the rotational axis and consisting of two helices interconnected in series at their lower ends, means communicating through said post with the upper ends of said helices for circulating attemperating fluid therethrough, and driving means for said coil extending through said post.
3. An attemperating apparatus of the character described comprising a vat, a vertical helical coil of elliptical cross-section rotatably supported

at its upper end only in said vat and being open at its lower end, a stationary baffle plate supported within said coil, said coil being centered on the rotational axis and consisting of two helices interconnected in series at their lower ends, and means communicating with the upper ends of said helices for circulating attemperating fluid through said coil. 5

4. An attemperating apparatus comprising a vat, a stationary vertical post in said vat extending upwardly from the bottom thereof above the normal liquid level therein, a helical coil of elliptical cross-section open at its lower end rotatably supported at its upper end only by said post, driving means for said coil, said coil being centered on the rotational axis and consisting of two helices interconnected in series at their lower ends, and means communicating through said post with the upper ends of said helices for circulating attemperating fluid through said coil. 10 15 20

5. An attemperating apparatus comprising a vat, a stationary vertical post in said vat extending upwardly from the bottom thereof above the normal liquid level therein, a helical coil of elliptical cross-section open at its lower end rotatably supported at its upper end only by said post, a stationary baffle supported within said coil, driving means for said coil, said coil being centered on the rotational axis and consisting of two helices interconnected in series at their lower ends, and means communicating through said post with the upper ends of said helices for circulating attemperating fluid through said coil. 25 30 35

6. An attemperating apparatus comprising a vat, rotatable means supported by said vat, a helical coil of elliptical cross section carried by said means and centered on the rotational axis thereof, a stationary baffle plate supported within said coil and means for circulating attemperating fluid through said coil. 40

7. An attemperating apparatus of the character described comprising a vat, a helical coil of elliptical cross-section rotatably supported at its upper end only in said vat and being open at its lower end, a stationary baffle plate supported within said coil and means for circulating attemperating fluid through said coil. 45
